J. S. MEAD

NECKTIE HOLDER

Filed March 22, 1920

Fig. 3. INVENTOR:

James S. Mead

BY *Allen Hollis*
ATTORNEYS.

UNITED STATES PATENT OFFICE.

JAMES S. MEAD, OF CINCINNATI, OHIO.

NECKTIE HOLDER.

Application filed March 22, 1920. Serial No. 387,741.

To all whom it may concern:

Be it known that I, JAMES S. MEAD, a citizen of the United States, and a resident of Cincinnati, in the county of Hamilton and State of Ohio, have invented certain new and useful Improvements in Necktie Holders, of which the following is a full, clear, and exact description, reference being had to the accompanying drawing, forming part of this specification.

The object of my invention is to provide a holder upon which a four-in-hand tie can be tied which shall retain the tie in completed shape so that it can be adjusted in position and taken off without untying the knot and with which when desired the material can be retied in a new position so as to shift the material as it becomes worn. With this holder I obtain the advantages of a permanent tie at the same time that I have the advantage of shifting the position of the knot so as to utilize a larger portion of the material. Above all, the tie once formed retains its permanent position and need not be untied and retied except at rare intervals to expose a fresh part of the goods.

My invention consists of a plate of suitable material, preferably of sheet metal, formed in the shape of the knot of the four-in-hand tie, and so constructed that the loose end which passes around the neck need not be passed through the knot, but will be held by the mere catching of the same under a portion of the holder.

In the drawing,

Figures 1 and 2 are front and rear elevations of my novel holder.

Figure 3 is a top plan view.

Figures 4, 5, 6 and 7 illustrate the rear portion of the tie showing the various steps of inserting the holder, and Figure 8 is a rear view of the completed tie, showing the method of securing the free end around the neck.

The holder is comprised of a shield or plate 1, substantially of the shape of the four-in-hand knot, slightly curved transversely as shown in Figure 3, and with the upper edge of the shield 2 formed somewhat diagonally of the longitudinal axis of the plate. The plate 1 is provided with a lateral extension somewhat narrow, which is turned over to the rear of the plate at 3 and then extends downwardly at 4, in line with the longitudinal axis of the plate, a slight distance beyond the lower edge of

the plate. This tongue 4 may have a reinforced rib 4^a.

It is contemplated in making up the shield that the tongue and body of the shield shall be stamped out of a piece of sheet metal so that the tongue when folded back will take the position as shown in Figure 1. The outer longitudinal edge of the portion 4 is preferably formed with a series of serrations 5. This tongue will be somewhat resilient and as will be described, is preferably serrated in order to more effectually hold the fabric of the tie which is to be passed thereover. Instead of constructing the holder and tongue integrally of sheet metal, wire can be substituted for the rear portion, the same to be soldered or otherwise permanently fastened to the body of the shield near the upper corner.

To insert the holder in the tie, a simple knot is first formed in the tie material 6, in which 7 is the broad end of the four-in-hand tie, and 8 a portion of the free end, which in such ties is quite narrow and forms the portion that passes around the neck. With the back of the knot toward the operator and with the holder facing the operator, the tongue 4 is passed down into the loop 9 in the tie until the holder takes the position shown in Figure 5. The holder is then turned over into the position shown in Figure 6, which brings the back portion of the holder facing the operator, and with the tongue 4 carrying the tie material looped around it at 10. The upper edge 12 of the holder is then in a position to allow the loop 13 of the tie to be pushed down over the holder as shown in Figure 7. The tie will then be complete, and will have the appearance and shape of the ordinary four-in-hand tie when in use. In order to fasten the tie in place, the knot is placed underneath the collar in front and the loose narrow end 14 passed around the neck and slipped under the tongue at 10, where it will be held by the resiliency of the tongue or by the serrations 5.

In use, the tie can be used as if permanently knotted, and the loose end merely slipped from under the tongue in order to remove the tie.

The fact that it is not necessary to untie and retie the goods every time the necktie is used, adds very much to the life of the fabric.

Having thus described my invention, what

I claim as new and desire to secure by Letters Patent is:—

1. In a device of the character described, the combination with a plate formed to present the facial contour of a four-in-hand knot, of a tongue secured to the upper portion of said plate and spaced therefrom to extend downwardly behind the plate and free therefrom below, whereby when the 5 four-in-hand knot of the tie is formed, the tongue may be inserted into the side loop of the tie and the fabric folded over, the opposite side loop of the knot secured over the free edge of the facial contour member, and the free end of the tie secured under the tongue.
2. In a device of the character described, the combination with a plate formed to present the facial contour of a four-in-hand knot, of a tongue mounted on said plate and 10
- 15
- 20

spaced therefrom to extend downwardly behind the plate and free therefrom below, whereby when the four-in-hand knot of the tie is formed, the tongue may be inserted into the side loop of the tie and the fabric 25 folded over, the opposite side loop of the knot secured over the free edge of the facial contour member, and the free end of the tie secured under the tongue.

3. In a device of the character described, 30 the combination of a plate formed in the contour of the face of a four-in-hand knot, with a member extending therefrom in shape of a tongue, said tongue running from the corner of widest dimension of the plate, thence inwardly and downwardly substantially centrally of the plate, and spaced therefrom toward the narrow end of said plate, as and for the purpose described.

JAMES S. MEAD.
